UNITED STATES PATENT OFFICE.

ROBERT MIEHLE, OF CHICAGO, ILLINOIS.

SHEET-DELIVERY APPARATUS FOR PRINTING-MACHINES.

SPECIFICATION forming part of Letters Patent No. 398,642, dated February 26, 1889.

Application filed March 21, 1887. Serial No. 231,786. (No model.)

To all whom it may concern:

Be it known that I, ROBERT MIEHLE, of Chicago, in the county of Cook and State of Illinois, have invented certain new and useful 5 Improvements in Sheet-Delivery Apparatus for Printing-Machines, of which the following is a specification.

The present invention relates to sheet-delivery for cylinder printing-presses in which 10 the sheet can be delivered at the front or top of the cylinder; and it consists of two sets of revolving delivery-grippers or delivery-cylinders for delivering the sheet to the fly-frame.

In the accompanying drawings, Figure 1 is 15 part of a side view in elevation of a two-revolution cylinder printing-press with the improved sheet-delivery attached thereto. Fig. 2 is a front view of the same. Fig. 3 is a side view of one of the adjustable reels. Fig. 4 is 20 a sectional end view of the second delivery-cylinder.

A designates the main frame of the press; B, the impression-cylinder; B', the feed-board, and B² the cylinder-grippers. In the frame A' 25 is mounted shaft D, upon which are secured brackets a, holding delivery-rod a², supporting the delivery-grippers or sheet-lifters a'. These grippers take the sheet from the impression-cylinder, through the action of the usual 30 spring, a³, and cam a⁴, by the wiper a⁵ of spring a³, and cam a⁴, by the wiper a⁵ of crank a⁶, rolling upon cam a⁴. The reels D' upon shaft D support the sheet as it is passed to the delivery-cylinder E, which has grippers b upon rod b', which are operated, through 35 spring b² and cam b³, by the wiper b⁴ upon the crank b⁵ rolling on cam b³.

The fly-frame or receiving-fingers G are held upon rod G', which is journaled in frame A at the front end of the press. The mechanism 40 for operating the fly-fingers it is thought unnecessary to show, as this operation is well-known.

Motion is communicated to the delivery-cylinders by gearing, which is but partly shown 45 to more clearly show the other parts of the device.

The portion marked v on the impression-cylinder shaft U meshes with the gear w on the shaft D. This in turn meshes with the 50 parts x, this being the gear secured upon the shaft of the delivery-cylinder E.

The delivery of the sheet is as follows:

After the sheet has been printed and is brought around by the impression-cylinder grippers B², the delivery-grippers or sheet-lifters a' seize the forward edge of the sheet and carry it around to the upper cylinder, E, the grippers b of which then seize it and carry it around the top of the cylinder and discharge it upon the fly-fingers G, the ends of which bear against the cylinder E, as shown in Fig. 4, the said fingers stripping the sheet from the cylinder as it continues to revolve. The sheet is then lifted bodily by the fly-fingers and deposited upon the receiving-table 65 G². It will be noticed that when the open part of the cylinder E is at the point shown in Fig. 1 the fly-fingers G rest upon rod i, which brings the end of fingers G below the periphery of cylinder E, and as the cylinder is moved 70 forward the end of fingers G will ride upon the incline y, which insures the sheet being passed over the fingers. The pulleys i' serve to assist the sheet traveling down the fly-fingers. The same receive motion from gear 75 N, a portion of which is shown in Fig. 1 and wholly in Fig. 2. This gear meshes with gear x and communicates motion to gear N' upon rod i. The riding-pulley I, secured on rod O, which has a rubber surface, also serves to 80 assist the sheet traveling down upon the fly-fingers, and is also used for cutting the sheet by placing a circular knife thereon which extends into a groove cut in the cylinder E.

In order to remove the reels readily whenever desired, (as in most cases they are entirely dispensed with,) the shaft D is cut away, as shown in Fig. 3, to allow the reel (which has its hub cut away) slipping over the same, enough of the hub being left to secure the reel 90 with the set-screw upon the shaft D.

The opening in the hub of reel D' is sufficient to clear the brackets a, which are secured to the shaft D. This allows the reels to be adjusted lengthwise upon shaft D. 95

The reels D' may in some cases be substituted with a cylinder like cylinder E, or cylinder E may be substituted with reels, whichever way desired. Motion may also be communicated to the delivery device or cylinders 100 by irregular gearing or a cam motion and gearing which would be desirable in stop-cylinder presses.

It is held that other devices may be substi-

tuted instead of the fly-fingers G to remove the sheet from the delivery-cylinder or reels E, or the said cylinder may be set at any point around the sheet lifters or grippers 5 without departing from the spirit of my invention.

What I claim as my invention, and desire to secure by Letters Patent, is—

1. The combination, with the impression-cylinder, of a series of revolving sheet lifters or grippers, and a receiver-cylinder journaled at the front or top of the cylinder to seize the edge of the sheet and deliver it to a delivery-cylinder, said delivery-cylinder discharging 15 the last (or freshly) printed side away from the receiving devices, substantially as described.

2. The combination, with the impression-cylinder, of a series of revolving sheet lifters 20 or grippers, a revolving delivering-cylinder and receiving-fingers journaled at the front or top of the cylinder to seize the edge of the sheet and deliver it to a revolving delivery-cylinder, which in turn delivers it to a series 25 of fingers with the last or freshly printed side

away from the fingers, substantially as described.

3. The combination, with the impression-cylinder, of two sets or series of revolving sheet lifters or grippers journaled at the front 30 or top of the cylinder, and a reel or reels revolving with said grippers to support the sheet as it is delivered to the second set of delivery-reels, the same delivering the sheet to the receiving devices with the last or 35 freshly printed side away from the same, substantially as described.

4. The combination of the impression-cylinder, sheet-lifters a', delivery-cylinder E, fly-fingers G, and pulleys i, substantially as and 40 for the purpose set forth.

5. The combination of the impression-cylinder, revolving sheet-lifters a', delivery-cylinder or reels E, stripping-fingers G, and pulleys i, 45 said pulleys receiving motion by gearing from the cylinder E, substantially as described.

ROBERT MIEHLE.
